CLAIM

The ornamental design for a book clip lamp, as shown and described.

DESCRIPTION

FIG. 1 is a first perspective view of a book clip lamp showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

The broken lines shown in the drawings depict portions of the book clip lamp in which the design is embodied that form no part of the claimed design.
